IMPROVEMENT IN CIGAR PRESSES.

GEORGE HEISS, OF LANCASTER, PENNSYLVANIA.

Letters Patent No. 59,911, dated November 20, 1866.

SPECIFICATION.

TO ALL WHOM IT MAY CONCERN:

Be it known that I, GEORGE HEISS, of Lancaster, in the county of Lancaster, and State of Pennsylvania, have invented a new and improved device for Pressing Cigars; and I do hereby declare that the following is a full, clear, and exact description of the construction and operation of the same, reference being had to the accompanying drawings making a part of this specification, in which—

Figure 1 shows an ordinary press with my improvements in place.

Figure 2, one form of a single mould case or press, resting on its removable bottom O, held by pins.

Figure 3 shows the top, P, with a series of ledges, H, and pins, I.

Figure 4 shows the open cells of the central press frame with the top, P, and bottom, O, removed to exhibit the blocks, E, perforated for the rod, G, and springs, F.

Figure 5 shows a mould case or pressing frame of full size—four feet long, nine inches wide—upon a filling-in board, L, provided at each end with a raised flange and handled screw, D'.

Figure 6 illustrates a six angled-cigar, or modes of pressing other forms than square.

The facility of packing and demand for pressed cigars have induced tobacconists to invent devices to accomplish that object, and already various inventions have been made. After trial, in my extensive factory, of several modes, I have found the following superior to any before tried: I use an ordinary press, (fig. 1,) four feet long in the clear, and nine inches wide, with a projecting ledge, R, on each side in the rear, against which the ends or back corners of the cases are pushed as they are piled one upon the other, being a vertical gauge, which also brings the front of the cases plumb under the press screws. On each of the vertical sides of the press in front, I have a board, Q, with slots and binding-screws, S, so that when the cases are in place, these boards, Q, are slid in to hold the boxes at the front corners, and screws, S, are tightened so that the cases numbered 1, 2, 3 to 10, are firmly held in place centrally under the screws while pressing, a plan superior to side grooves and tongued press-boards. I am not aware that adjustable side slides, Q, and back strips, R, have ever before been used for pressing cases and keeping them in place. Fig. 5 shows a full-sized frame with its cross-slats upon its bottom, O, placed upon a filling-in board, L'; this filling-in board has a front and rear ledge, L, (shown only on one side, or end,) the height of the combined bottom O, and press frame A, B, C; a threaded bur or female screw centrally, or a handled screw, D', on the end of which there is a forked piece, K, to admit the front end, A, of the press frame; the lower ledge, N, is admitted into a groove n cut in the bottom O, under the frame. On the upper prong of K, there is a piece, M, held by a pivot, so that it may be turned up; and when the frame piece, A, is embraced, the lock or press block, M, is turned down against N or lower prong, and fills the space between the outer end, A, of the frame, and the inner sliding cross-piece B, so that when the screw handle is turned the pressure is given to the slats and cells the same as if a screw were affixed to each end of the press frame, as shown by figs. 2, 4. And by means of a single filling-in board, all the frames can be pressed or the cells screwed up to the gauge, and held in that position by inserting a key or plug, T, as a wedge between A and B, when the top, P, is put on, and, pressing the frame or case removed, and another empty frame placed upon the filling-in board filled, and the cigars pressed on one side until all the combined cases are filled and placed upon the press, fig. 1, where the other side of each cigar receives the final pressure and finish. The construction and operation of my open frames will be readily understood by inspection of fig. 4, which shows a frame, A C, with a screw, D, centrally on each end piece A. These pieces are also braced by a headed rod, G, on each side with a screw and bur at the other end. Over these rods, G, the one sliding piece, B, is inserted; then a short block, E, with a perforation for a short spiral spring, F, around the rods, G, on each side; then a slat, 5', and block with spring, and so on, slat after slat, with their respective blocks, E, and springs, F, to the centre of the frame. The central slat, marked 1, may be framed in or firmly fastened to the frame, the succeeding slats, blocks, and springs, movable on the rods to the final sliding cross-piece, B. Fig. 4 shows the upper portion of the frame with its cells for containing the cigars closed up to the blocks E. The lower portion shows the cells relaxed, and the action of the springs, the position the cells are in when they are used for filling-in, placed upon the bottom board, O, or for dislodging the cigars after they have had their requisite pressure both ways. Fig. 2 shows the press frame on its bottom held by pins on the bottom entering holes in the lower side of the frame, similar to those shown on the top at C, for the pins, I, in top, P, fig. 3. When the cells are opened, (by turning the screw the springs act and separate the slats,) the cells are filled with the fresh-made cigars, and then screwed up from both sides, either by the screws on each end, or the screws, D', on the filling-in board; when screwed up as far as

the gauge blocks, E, admit, the slatted top, P, is put down upon the frame. These slats fit into the cells, (H fig. 3,) by inserting the pins, I, into the holes, C, in the frame, and when placed, with others, under the large press, fig. 1, the slats, H, on the top P, press between the slats in the frame or cells containing the cigars, and flatten the top and bottom of the cigar having the sides previously pressed between the slats in the frame, completing the pressure, and giving the cigar a superior finish. The expanded cells afford the greatest facility, and can be filled with great ease in a very short time, pressed between the slats, the top put on, placed in the large press with despatch, and are much easier dislodged than when placed in alternate cells made by the union of two pieces with flexible backs, as the curving process is less satisfactory than when the cells open and dislodge them at once in regular layers.

Believing the description full and clear, and readily comprehended by the drawings, this description may suffice to enable any one skilled to make the same.

I am aware that a combination of two flexible pieces—top and bottom—each with slats of uniform height and width, so made as to mesh one into the other, have been used, leaving alternate spaces or cells by means of higher side pieces for the purpose of pressing cigars; I am also aware that metallic strips have been used between two boards held in slits made at regular intervals, between which the cigars previously flattened are placed into the cells and then pressed; so with the former device the cigars are also flattened by pressure before they are inserted in the cells. They are put directly into my expanded cells as they come from the hands of the workmen. When the top and bottom are removed, my cells are open above and below and the sides relaxed, and no possible injury can befall the wrappers by sticking or otherwise.

I disclaim the foregoing mentioned devices. What I claim as my invention, and desire to secure by Letters Patent, is—

1. The frame A A, C C, with its movable ends B, and slats 1, 2, 3, 4, &c., in combination with the rods G, springs and blocks E F, arranged and operating in the manner and for the purpose specified.
2. I also claim the arrangement of the open frame A C, and its parts, in combination with the top P, with its slats H, and pins I, and bottom O, substantially made and used for the purpose specified.
3. I also claim the construction of the filling-in board L, with its handled screws in combination with the with the forked terminus K, N, turning press block M, when employed for the purpose and the manner specified.

GEORGE HEISS.
